UNITED STATES PATENT OFFICE.

NORMAN SCOTT HAMLIN, OF MARYSVILLE, CALIFORNIA.

SYRINGE-BOTTLE.

SPECIFICATION forming part of Letters Patent No. 351,105, dated October 19, 1886.

Application filed June 30, 1886. Serial No. 206,752. (No model.)

To all whom it may concern:

Be it known that I, NORMAN SCOTT HAMLIN, of Marysville, Yuba county, State of California, have invented an Improvement in 5 Syringe-Bottles; and I hereby declare the following to be a full, clear, and exact description of the same.

My invention relates to syringe-bottles; and it consists in a bottle having a neck-opening 10 in its side and a removable elastic band covering said opening and encircling the bottle, as I shall hereinafter fully describe and claim.

The object of my invention is to provide a bottle, the neck-opening of which can be easily 15 and tightly closed by means of an elastic band, which is also readily removable for the insertion of the point of the syringe.

These bottles have been heretofore carried in a case specially prepared for them, and 20 which also contains the hypodermic syringe and whatever accessories may be necessary for the operation. The bottle lies upon its side in the case, with its neck-opening turned upwardly, and said opening has usually been 25 closed by a simple stopper, the removal of which affords ready access to the contents of the bottle. It has, however, been difficult with such a stopper to keep the bottle from leaking. This difficulty is overcome entirely 30 by my invention, which effectually prevents any leakage, and affords great convenience in obtaining access to the contents of the bottle.

Referring to the accompanying drawings for a more complete explanation of my invention, 35 Figure 1 is a perspective view of my bottle. Fig. 2 is a longitudinal section of the same.

A is the bottle or vial, both ends of which are closed, and the neck B is in the side of the bottle, near one end.

C is an elastic band covering the opening of 40 said neck and encircling the bottle. It is held in place tightly by its own elasticity, and can be readily placed in position and as easily removed.

In order to make the band fit the neck-opening 45 perfectly, I concave the outer end of the neck, as shown, so that the pressure of the band draws it in tightly around the opening, as will be seen plainly from the drawings. The pressure of the band is sufficient to make a 50 tight joint, and the contents of the bottle will not be wasted by leakage.

When the bottle is lying in its case with its neck turned upwardly, the band can be slipped off, either wholly or partially, from the neck-opening, to afford access to the point of the 55 syringe.

I am aware it is not broadly new to form an opening in the side of a bottle, and to cover said opening with a removably-secured 60 flexible stopper, and such construction I therefore do not broadly claim as my invention.

Having thus described my invention, what I 65 claim as new, and desire to secure by Letters Patent, is—

The syringe-bottle A, having closed ends and a neck projecting from one side having its end concaved, in combination with an elastic removable band covering and fitting the concaved open end of the neck and encircling the 70 body of the bottle, as herein described.

In witness whereof I have hereunto set my hand.

NORMAN SCOTT HAMLIN.
